UNITED STATES PATENT OFFICE.

JAMES J. BOIS, OF RANTOUL, ILLINOIS.

IMPROVEMENT IN GRAIN-SAMPLERS.

Specification forming part of Letters Patent No. 143,953, dated October 28, 1873; application filed September 10, 1873.

To all whom it may concern:

Be it known that I, JAMES J. BOIS, of Rantoul, Champaign county, Illinois, have invented, made, and applied to use a new and useful Sampler for Sampling Grain; and that the following is a full, clear, and correct description of the same, reference being had to the accompanying drawing making part of this specification, and to the letters of reference marked thereon, in which—

Figure 1 is a side elevation of my grain-sampler. Fig. 2 is a front view of the same. Fig. 3 is a side sectional view of the same. Fig. 4 is a sectional view through line 1 2 of Fig. 3 of the drawing.

In the drawings, like parts of the invention are designated by the same letters of reference.

The nature of the present invention consists in the construction, as more fully hereinafter set forth, of an improved device for sampling or testing grain, more particularly corn; the object of the invention being the production of a device for such purpose which shall be afforded at a low cost, and shall be simple and direct in its operation.

To enable those skilled in the arts to make and use my invention, I will describe the same.

A shows a triangular-shaped receptacle for the grain or corn, formed of tin or any suitable metal, and divided into a series of compartments by means of the division-plates *a*. This receptacle A is provided with the point *C*, and flanges *e*, and lip *c*. Over the flanges *e* the lipped portions *d* of the cover B are passed, while beneath the lip *c* the lower end of the

cover B is received. B shows the cover, formed of tin or any suitable metal, intended to be passed over the receptacle A, being provided with the lipped portions *d*, sliding over the flanges *e*. The cover B is also provided with the projecting plate *b* and handle *b'*. The receptacle A is provided with the handle *a'*.

Such being the construction, the operation may be thus explained: The sampler is inserted into a sack of grain, (the point *C* and projecting plate *b* assisting materially the insertion of the sampler,) and having been inserted to its full extent, the cover B is then elevated, and the grain enters and fills the compartments of the receptacle A. After the compartments are filled the cover B is closed upon the receptacle A by thrusting it down, and the sampler is then withdrawn from the sack of grain, and on opening the lid or cover the quality of the grain contained in the sack is ascertained by an examination of the grain contained in the compartments of the receptacle A.

Thus it will be seen that sacks of grain, or grain packed in other receptacles, can be expeditiously and accurately sampled.

Having now set forth my invention, what I claim as new is—

The combination of the receptacle A, provided with the compartments and point *C*, with the cover B, constructed as shown, substantially as and for the purpose set forth.

JAMES J. BOIS.

In presence of—

W. G. BARROWS,
HERMAN BÖHNE.
